UNITED STATES PATENT OFFICE.

JAMES ROSENBERG, OF CLEVELAND, OHIO.

DEVICE FOR PRINTING INTERSECTING LINES.

Application filed August 23, 1920. Serial No. 405,406.

To all whom it may concern:

Be it known that I, JAMES ROSENBERG, a citizen of the United States, and a resident of Cleveland, county of Cuyahoga, and State 5 of Ohio, have invented a new and useful Improvement in Devices for Printing Intersecting Lines, of which the following is a specification, the principle of the invention being herein explained and the best mode in 10 which I have contemplated applying that principle, so as to distinguish it from other inventions.

The present invention relates to an improved means for printing lines for ruled 15 pages or forms on a cylindrical printing press, either in large numbers, or such a printing press as a multigraph or the like. The present improvements are particularly designed for use on multigraphs which are 20 of great value in printing forms of light impression.

The principal advantage of the present invention is that it provides a system of interlocking members which may be assembled anywhere, and then mounted upon the cylindrical drum of a printing press or multigraph or may be assembled on a press and there locked into position. Any variety 25 of spacing of the lines can be secured in the present system, and obviously the system is not limited to use on a cylindrical press, as it may also be used to advantage in ordinary flat form printing. To the accomplishment 30 of the foregoing and related ends, the said invention, then, consists of the means herein-after fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawings:—

Fig. 1 is a plan view of a series of my improved elements assembled together for printing a ruled form; Fig. 2 is a view in perspective of one of the spacing or interlocking elements; Fig. 3 is a similar view of one of the printing elements designed to be received in the element of Fig. 2; Fig. 4 is an end elevation of the spacing element shown in Fig. 2; Fig. 5 is a similar view showing a modification of the element; Fig. 55 6 is still another view showing another modification; Fig. 7 is a transverse sectional

view of an assembly of my various printing and spacing elements; Fig. 8 is a section on the line 8—8 Fig. 7; Fig. 9 is a section on the line 9—9 Fig. 7; Fig. 10 is a transverse 60 section through a spacing bar with a printing bar adjacent thereto; Fig. 11 is a view in perspective showing the method of assembly of the spacing element and the elements for printing intersecting lines; Fig. 12 is a 65 plan view of an assembly of my improved elements mounted on the surface of a cylindrical drum; and Fig. 13 is a transverse section on the line 13—13 of Fig. 12.

The nature of my invention can best be 70 understood from the inspection of Figs. 1, 2, 3 and 11. In Fig. 1 I have shown the various elements assembled and adapted to print a form in which there are transversely extending lines 1 and longitudinally extending lines 2 intersecting the transverse lines. For printing a form such as indicated in this figure, I use a series of interlocking and spacing bars 4 which may be termed gauges, 75 since they act to gauge the distances between the other elements. Each of these bars 4 is provided with a series of equidistantly spaced and similarly shaped laterally extending flanges or gauging teeth 5. These teeth extend on either side the central body 80 portion of the spacing bar, and are themselves separated by a longitudinally extending groove or recess 6 which is adapted to receive a printing element 7 carrying a 85 printing character 8 which may be either a straight edge for the purpose of printing a line or some other printing character as may be desired. The two lower corners of the spacing element 4 are cut away to provide 90 recesses 9 for a purpose which will presently 95 be described. The teeth 5 on the gauges form between them recesses 60 adapted to receive other elements presently to be described.

In setting up the form shown in Fig. 1 100 there are used, for example, four longitudinally extending spaced gauge bars 4. In the central groove 6 of each of these bars are inserted printing bars such as are shown in Fig. 3 carrying elements for printing lines which produce vertical lines on the page to be printed. For printing the transverse lines I employ a series of thin printing bars 10 which are shown in Figs. 105 10 and 11, and which may be snugly inserted between the spaced lugs or flanges 5 on the spacing bars. The ends of these bars 110

10 are formed as indicated in Fig. 10, and are so constructed as to fit snugly against the printing elements 8 or lines on the element 7, and also against the body portion 5 of the spacing bar 4. In this way the bars 10 may be brought to the same printing height as the bars 8, and intersecting lines may be printed in this manner as many bars 10 being used as there are transverse lines 10 desired in the finished page. In Fig. 10 I have shown the construction and character of engagement between the gauge bars 4 and the printing bars 10. The gauge bars are engaged between their teeth 5 in the recesses 60 by the printing bars, the latter locking over the extending portions 40 of the gauges. Also the projection 41 on the bar 10 contacts against the lateral surface 42 of the printing element 7 while the lower surface of this projection rests on the shoulder 43 on this printing element. The recess 44 of the member 10 is constructed to engage over the portion 40 of the gauge with sufficient clearance to allow for convenient engagement thereover. A slight play in this engagement is not objectionable since it is only necessary that these members interlock, while the height is maintained by the positioning of all members on the same base. That is, the elements 10 have the same height as do the elements 7 when mounted on the gauge 4.

In Fig. 7 I have shown a longitudinal section through an assembly of parts arranged for printing lines. In this view the gauges 4 are shown in spaced parallel relation carrying the line-printing elements 7. While the bars 10 (not shown in this figure) will maintain the relation between the gauges, intermediate parts 50, known as spacing furniture, may also be used either with the bars 10 or in places where no bars are desired. These elements 50 are formed to engage laterally with the gauges and are similar thereto except that they carry no printing elements, while they have lateral projections 51 engaging in the notched out corners 9 of the gauges.

After the printing elements have been assembled in the manner indicated in Fig. 1 they may be mounted about a cylindrical drum 15 by a cylindrical printing press as shown in Fig. 13, the printing press being, of course, either the usual cylinder press or a multigraph. When so mounted they are locked in position by means of transversely extending end locking elements 16 which are of L shape and provided with holes 17 adapted to receive bolts 18 adapted to lock into longitudinally extending grooves 19 formed into drum 15. The upwardly extending portion of the L shaped members 16 are provided with downwardly extending flanges 20 which engage between the spaced teeth 5 on the spacing gauges

and lock the same in position against the surface of the cylindrical drum.

The present invention provides a means for printing intersecting lines on cylindrical presses while permitting the setting up of 70 the printing elements anywhere as on a flat form or page after which they may be locked in position on the cylinder. It is of particular value in connection with a multigraph as it very greatly enlarges the field 75 of usefulness of such a machine, and enables it to print numerous varieties of office forms which are today so largely in use.

Other modes of applying the principle of my invention may be employed instead of 80 the one explained, change being made as regards the mechanism herein disclosed, provided the means stated by any of the following claims or the equivalent of such 85 stated means be employed.

I therefore particularly point out and distinctly claim as my invention:—

1. In mechanism for printing intersecting lines, the combination of a gauge element provided with a plurality of recesses extending transversely along one side, and a longitudinally extending recess along its upper face and said gauge being adapted to receive a line printing type element on its upper surface, and a line-printing type bar adapted 95 to engage in one of such recesses in said gauge element.

2. In mechanism for printing intersecting lines, the combination of a spacing gauge provided with a plurality of equidistantly spaced recesses along one lateral side and a longitudinally extending recess along its upper face, a printing element removably mounted in such recess, and a line-printing bar adapted to engage in one of such recesses 100 along the side of said gauge and lock therein, said bar being adapted to also engage with said line element and the upper surface 105 of said gauge.

3. In mechanism for printing intersecting lines, the combination of a spacing gauge provided with a plurality of equidistantly spaced recesses along one lateral side and a longitudinally extending recess along its upper face, a printing element removably mounted in such recess, and a line-printing bar adapted to engage in one of such recesses along the side of said gauge and lock 115 therein, said bar being adapted to extend into contact with said element on said gauge.

4. The combination with a cylindrical drum, two gauge elements extending around said drum in parallelism, said gauges being provided with lateral recesses, line-printing elements extending between said gauges and engaging in such recesses, and means locking 120 said gauges to said drum.

5. The combination with a cylindrical drum, two gauge elements extending around said drum in parallelism, said gauges being 125

provided with lateral recesses, line-printing elements extending between said gauges and engaging in such recesses, and a locking bar disposed parallel to the axis of said drum and engaged therewith, said bar engaging the ends of said gauges and maintaining the same in position on said drum.

6. In a type system for printing intersecting lines, the combination of a gauge member provided with lateral recesses adapted to receive line-printing bars extending at right angles to said gauge, and said gauge being provided with an undercut longitudinally extending recess, and a line-printing type element removably mounted in such last named recess.

7. In a type system for printing intersecting lines, the combination of a gauge member provided with a series of equidistantly spaced parallel walled recesses along one side, a line-printing element provided with an end portion adapted to engage with one of such recesses and to be locked against substantial vertical movement with respect to said gauge.

8. As a new article of manufacture, a spacing and interlocking gauge for a type system comprising a bar provided with a type-element receiving groove along one face and a series of spaced recesses along a second face at right angles to the first named face.

9. As a new article of manufacture, a spacing and interlocking gauge for a type system comprising a bar provided with a type-element receiving groove along one face and a series of spaced recesses along two faces each at right angles to such first named face.

10. As a new article of manufacture, a spacing and interlocking gauge for a type system comprising a flexible metal gauge strip provided with a type-element receiving groove along its upper face, and a series of recesses along its sides, said strip being constructed to adapt it to be bent around in contact with a curved drum.

Signed by me, this 21st day of August, 1920.

JAMES ROSENBERG.
